UNITED STATES PATENT OFFICE.

FREDRICK MENGLE BOWERS, OF CHESTER, PENNSYLVANIA.

HELMET.

1,135,759.

Specification of Letters Patent. Patented Apr. 13, 1915.

Application filed January 7, 1914. Serial No. 810,898.

To all whom it may concern:

Be it known that I, FREDRICK M. BOWERS, a citizen of the United States, and a resident of Chester, in the county of Delaware and 5 State of Pennsylvania, have invented a new and Improved Helmet, of which the following is a full, clear, and exact description.

My invention relates to helmets or masks, and has reference more particularly to a 10 mask used in electric arc and autogenous welding and cutting.

An object thereof is to provide an efficient, simple, light and inexpensive helmet or mask which can be easily placed from operative 15 to inoperative position without removing the same from the head of the wearer, which helmet or mask affords a large angle of vision when in use, leaving both hands of the wearer free for work.

20 A further object of the invention is to provide a helmet or mask substantially the entire area of which is disposed angularly to the rays of the welding or cutting flames, thus preventing the penetration of rays by 25 deflecting them.

I attain the above objects by providing a helmet or mask having a convex surface adapted to present the said surface angularity to the rays and having a substantially 30 central visual opening, and a support whereby the mask can be secured to the head of the wearer and on which support said mask can be placed in operative or in inoperative position without disturbing said 35 support on the head of the wearer.

My invention relates to the construction and combination of parts to be more fully described hereinafter and fully set forth in the claims.

40 Reference is to be had to the accompanying drawings forming a part of this specification, in which like characters indicate corresponding parts in all the views and in which:

45 Figure 1 is a longitudinal section through an embodiment of my invention, as shown on lines 1—1, Fig. 3; Fig. 2 is a plan view of the same; Fig. 3 is a front elevation; and Fig. 4 is a front elevation of the frame 50 forming a visual opening.

55 Referring to the drawings, 5 represents a mask or helmet formed of two curved plates 6 and 7 connected to each other at the edge 8, from where they diverge from each other, the said edge 8 forming the front of the mask. The so connected plates 6 and 7 form

substantially a longitudinal half of a flattened ovoid forming the central, longitudinal edge 8. This mask differs from a knight's helmet in that it is more pointed in 60 the front, the reason for which will appear hereinafter. The mask 5 is provided with an aperture 9 diverging toward the front edge in the longitudinal plane of the mask.

Secured to the diverging edges of the plates 65 6 and 7 are members 10 whereby a substantially rectangular opening 11 is formed by

said members 10 and the curved plates 6 and 7, which opening appears to be recessed 70 from the front edge of the mask. Secured at the opening 11 to the edges formed by the plates 6 and 7 and the members 10 is a frame 12. Into said frame 12 are fitted glasses of red and blue color of proper density, of which 13 is the red glass and 14 75 the blue glass. It is understood that the relative position can be changed if desired. The reason for using the blue and red glasses is that the combination of the two glasses make a color distinction between the 80

melted metal and the slag present therein, which slag must be eliminated to obtain a perfect welding. The said glasses further protect the eye of the workman using the helmet from the ultra-violet rays. An ordinary 85 white glass 23 is placed in front of the colored glasses to protect the same from injury by the incandescent particles emitted during cutting or welding. The ordinary window glass protector can be replaced at 90 little cost. The said glasses are free to move in the frame 12 and maintained therein by means of catches 15 provided adjacent the corners of the recess for the glasses in the frame. The aperture 16 in the frame 12 95 forms the visual opening of the mask, and the visual angle is increased by the divergency of the aperture 9 in the mask.

Secured to the inner concave surface of the plates 6 and 7 are brackets 17, of which 100 each is pivotally connected to a member 18. The members 18 are carried by a skeleton band 19 adapted to encircle the head of the wearer, as shown in Fig. 1. A strap 20 connects the two members 18 and is adapted 105 to engage the upper part of the head of the wearer. A skull cap 22 is secured to the strap and band to protect the wearer from flying particles emitted during the welding or cutting. The said band 19 and strap 20 110 connected to the members 18 form a support for the mask, and in connection with the

mask form the helmet, so to speak, on which support the mask 5 can be revolved about the pivotal connection 21 between the brackets 17 and the members 18 and whereby the 5 said mask can be placed in operative or in inoperative position. When the mask is in inoperative position, the frame 12 will come in contact with the head of the wearer and maintain the said mask as a cask, thereby 10 leaving the face of the wearer free.

The reason for making the mask in the shape of a flattened semi-ovoid is to present a convex surface to the rays of the welding or cutting flame, which will be deflected by 15 said surface, and therefore, eliminate the danger of penetration of said rays therethrough. The surfaces presented by the members 10, particularly the upper one, may at certain intervals be perpendicular to the 20 rays of the welding or cutting flame and the said rays can pass freely therethrough without coming in contact with the wearer of the mask, as can be seen from Fig. 1, as ample space is left between the front of the 25 mask and the wearer's face. The entire mask is, preferably, made of aluminum, thereby reducing its weight. The reason for using the blue and red glasses is that the best results have been obtained after long 30 experiment with said colors.

Having thus described my invention, I claim as new and desire to secure by Letters Patent:

1. In a helmet, a mask having a visual opening of two differently colored glasses and a colorless glass in front thereof forming a shield protecting the colored glasses, and means for securing the mask to the head.
2. In a helmet, a mask having a visual opening formed of two colored glasses and a plain glass in front thereof forming a shield for protecting said colored glasses, a support for said mask, and means whereby said mask can be placed in operative or in inoperative position on said support.
3. In a helmet, a mask having a visual opening; glasses screening said opening; and means for securing the mask to the head, said glass screening the opening being of red and blue color of the proper density, with a plain glass in the front thereof shielding said colored glasses from injury.
4. In a helmet, a mask having a visual opening; a series of contacting glasses screening said opening and consisting of plain window glass and red and blue glasses of proper density in the order stated from the front to the rear of the mask; a support for

said mask; and means whereby said mask can be placed in operative or in inoperative position on said support.

5. In a helmet, a mask having the shape of a flattened semi-ovoid, the flattened portion forming the front of said mask, said mask having an opening, a frame in said opening; 65 colored and plain glasses removably carried by said frame and forming a visual opening for said mask; a skeleton band adapted to encircle the head; a skull cap carried by said band; members carried by said band; and 70 means connecting pivotally said mask to said members whereby said mask can be rotated on said support.

6. In a helmet, a mask having the shape of a flattened semi-ovoid, the flattening forming a longitudinal frontal edge on the mask, said mask having a glass-screened, visual opening depressed from the edge, and means for securing the mask to the head.

7. In a helmet, a mask having the shape 80 of a flattened semi-ovoid, the flattening forming a longitudinal edge at the front, said mask having a central recess apertured at the bottom and converging from the longitudinal edge to the bottom; a plurality of 85 contacting, differently colored glasses screening the aperture and forming the visual opening for the mask; and means for securing the mask to the head.

8. In a helmet, a mask having a convex 90 surface diverging from the front to the rear and having the shape of the longitudinal half of a flattened ovoid, the flattening forming a longitudinal edge at the front of the mask, said mask having a visual opening in 95 the front depressed from the edge; a support for the said mask whereby the same is secured to the head; and means whereby said mask can be revolved on said support and be placed in operative or in inoperative position.

9. In a helmet, an aluminum mask having the shape of a flattened semi-ovoid, the flattening forming a central longitudinal edge at the front of the mask, said mask having 105 a visual opening depressed from the edge; differently colored glasses screening said visual opening; and means for securing the mask to the head.

In testimony whereof I have signed my 110 name to this specification in the presence of two subscribing witnesses.

FREDRICK MENGLE BOWERS.
